MOLD BLOWING APPARATUS

Heinrich J. B. Herbruggen, Cleveland, Ohio, assignor, by
mesne assignments, to Pettibone Muliken Corporation,
a corporation of Delaware

Application April 14, 1955, Serial No. 501,287

4 Claims. (Cl. 22—36)

This invention relates to the art of making sand molds, cores and the like and more particularly relates to improvements in apparatus for forming sand molds and cores by blowing sand into an enclosed cavity.

The improvements of this invention are particularly adapted for use in a sand blowing apparatus of the type in which sand is discharged from a chamber by means of an air stream and into a mold cavity formed by the flask, a top plate and a bottom pattern plate until the cavity is completely filled with sand. In simple molding, the drag and cope portions of the mold are usually formed independently in the apparatus which includes an arrangement for compacting the sand in each flask portion so that the completed mold or core will resist deformation under pressure by the poured metal.

A principal object of this invention relates to the provision of a multiple pattern carrier which reduces handling and increases production efficiency by permitting the pattern to be changed on one portion of the carrier while another mold or core is being formed on another part of the carrier.

Another principal object of this invention relates to a simplification in the apparatus for compacting sand in the flask or core box.

Briefly, in accordance with this invention a sand discharge chamber is operably supported on a frame in surmounting spaced relation over a flask lift table to define a flask receiving area therebetween. The frame also supports a movable multiple pattern carrier for presenting a selected pattern onto the lift table while removing another pattern therefrom. The mold or core is formed by discharging sand from the chamber into the mold cavity formed when the lift table clamps the flask against the discharge portion of the chamber. A spacer member is also movably supported on the frame for insertion between the sand discharge chamber and the flask and operates to increase the sand receiving volume of the mold cavity. After sand is discharged into the enlarged mold cavity, the spacer member may be removed and the sand compacted in the flask or core box by repeating the clamping action of the lift table to form a sand mold or core capable of resisting deformation under pressure of poured metal. Different spacer members may be used to vary the density of the sand. In conjunction with the foregoing, the lift table is controlled during removal of the spacer member to prevent separation of the mold from the pattern.

Additional objects and advantages of the improvements embodied in this invention will be apparent from the following description, the appended claims and the accompanying drawings, in which:

Fig. 1 is a perspective view of the sand blowing apparatus illustrating the cooperative disposition of the major features of the invention;

Fig. 2 is a horizontal section taken along the plane of the flask supporting rails with the flask removed in Fig. 1;

Fig. 3 is a plan view of an interchangeable spacer member for increasing the mold cavity volume;

2

Fig. 4 is a vertical section through the left hand column illustrating the movable support for the spacer member;

Fig. 5 is a partial vertical section illustrating the position of the operative members in the flask receiving area prior to clamping;

Fig. 6 is a partial vertical section illustrating the position of the operative members in the flask receiving area during the sand blowing operation;

Fig. 7 is a partial front elevation illustrating the pattern carrier and lift table assembly; and

Fig. 8 is a vertical section illustrating the position of the operative members in the flask receiving area after removal of the spacer member and prior to compacting.

Referring now more particularly to Fig. 1 of the drawings, there is shown a sand blowing apparatus for making molds or cores and embodying an upright frame having a base 10 supporting spaced vertical columns 11 and 12 which are connected together at the top by a cross head 14. A sand discharge chamber 15 having a removable blow plate assembly 16 is pivotally supported by spaced arms like 19 which are swingable about the column 12 to position the chamber 15 under a sand hopper 20 external to the frame. The base 10 also supports spaced flask rails 22 and 23 for receiving a cope or drag flask in aligned position beneath the sand chamber 15. Although not shown, the rails 22 and 23 may be provided with extensions to support a line of flasks or core boxes for successive presentation to the core blowing apparatus. Movement of the line would be periodically interrupted during the sand blowing operation and then resumed to present an empty flask or core box above the lift table 25 while the completed mold or core is discharged at the other end of the line. The flask lift table 25 is supported on a movable main plunger 26 in a lift cylinder 27 which is disposed within the base for operation in a conventional manner (Figs. 6 and 8). The lift table 25 is also provided with an auxiliary plunger 30 at its forward extremity which is disposed in a cylinder housing 31 forming part of the base 10. The main plunger 26 and the spaced auxiliary plunger 30 coact on the base to prevent rotation of the table 25 and are operated by hydraulic pressure of oil or the like to control the movement of the lift table in a manner to be hereinafter more fully described.

In normal operation, a drag pattern 17 or a cope pattern corresponding to the type of flask 13 mounted on the rails 22 and 23 would be positioned above the lift table 25 and fluid under pressure applied to lift the pattern and flask against the blow-plate assembly 16 of the sand chamber to form a sand receiving mold cavity as shown in Fig. 6. Blowing pressure is supplied to the chamber 15 through suitable conduits like 33 and control valves like 34 which may be controlled at the control panel 35 to discharge sand from the chamber 15 into the mold cavity. After formation of the mold or core has been accomplished, the control valves can be operated to terminate the blowing cycle and exhaust the chamber 15 through the stack 36. The controls may be selectively manipulated or may be coupled together to provide an automatic sand blowing cycle.

In order to increase the efficiency and production of the apparatus, the patterns are mounted on plates 38 and 39 respectively and each plate is in turn mounted in fixed predetermined position on a multiple pattern carrier assembly which can be moved to selectively position either the drag or the cope pattern plate below the flask rails 22 and 23 and above the lift table 25.

Referring now particularly to Fig. 2 in conjunction with Fig. 1, the pattern carrier assembly is shown as embodying a support 40 having a pair of legs 41 and 42 disposed at right angles to each other and mounted for

rotation about the column 12 with its vertex coincident with the vertical axis of the column. Each leg of the support 40 carries an open-ended frame 44 and 45 and the length of each leg is selected so that the path of travel of each frame will intersect the lift table 25 when the support 40 is rotated. The frames 44 and 45 have a substantially U-shaped configuration which is complementary to the periphery of the lift table 25. Their open ends face inwardly towards the lift table so that when they are rotated in the plane of the table 25 they will partially encircle the table and support the corresponding pattern above the table. Each frame pattern carrier is provided with suitable pattern location holes 46 and 47 which are adapted to receive pattern plate guide pins, and the lift table 25 is also provided with suitable dowel pins 48 and 49 for alignment with corresponding guide openings in the pattern plates all of which reduces time and effort in handling.

The mounting of the support 40 on the column 12 is accomplished by encircling the column 12 with a rotatable sleeve 50 which carries radially projecting arms 51 and 52 to which the support 40 is connected. With this arrangement, while one pattern and flask are clamped in sand blowing relation with the chamber 15 and a mold or core is being formed, an operator can be preparing another pattern on the other carrier for presentation to the sand blowing apparatus. Usually, in simple molding, the drag pattern would be mounted on one carrier and the cope pattern on the other carrier so that the two halves of the mold could be made in rapid succession. The pattern carrier assembly may be rotated on the column 12 by hand, or as shown in preferred form in the drawings, may be positioned by locating a motor 55 on a platform 56 on the base 10 and providing a friction wheel 58 on the motor shaft to frictionally engage and rotate the carrier support 40 about its axis. The driving motor 55 may be energized through the medium of conventional reversing switches to automatically present selected patterns in predetermined sequence.

After the flask or core box 13 has been filled with sand, the sand may be compacted so that it will resist deformation under pressure of poured metal. In accordance with this invention, the compacting is preferably accomplished by introducing a spacer plate 60 between the top of the flask 13 and the blow plate assembly 16 of the sand chamber to increase the sand receiving volume of the mold cavity (Fig. 6). After the enlarged cavity is filled with sand to a certain density, the spacer plate 60 is removed and the lift table 25 clamps the bottom pattern plate and the flask 13 against the blow plate assembly to compact the sand in the reduced cavity. The density of the compacted sand will depend upon the excess sand volume as determined by the thickness of the spacer plate 60. Hence, the sand density can be varied by using different spacer plates. This eliminates the necessity for extra squeeze platens and results in a similar design and more efficient operation.

The spacer plate 60 is of uniform thickness and has an opening 62 corresponding substantially to the boundary area defined by the walls of the flask 13 and is adapted to be aligned therewith. Since the spacer plate 60 and its opening 62 may vary with the desired sand density as well as the size and type of flask, provision is made to removably support any type of spacer plate in the work space between the flask and the chamber blow plate assembly. This provision includes a U-shaped member 63 which is carried by a sleeve 64 concentrically mounted on the column 11 and rotatable on suitable bearings as best shown in the partial section view in Fig. 4 of the drawings. The member 63 carries suitable dowel pins 66 and 67 which are adapted for alignment with openings 68 and 69 in the spacer plate 60.

Thus, once a particular flask 13 is placed on the flask rails 22 and 23 above the corresponding pattern plate and before the lift table 25 is activated, the spacer plate

60 is swung about the column 11 into the space between the top of the flask 13 and the blow plate assembly 16 of the chamber 15 as shown in Fig. 4 of the drawings. The lift table 25 is then moved to clamp the bottom pattern plate, the flask and the spacer plate together against the blow plate assembly and the sand mold or core is blown in the usual manner (Fig. 6). Thereafter, the lift table 25 lowers the bottom pattern plate and the flask a distance sufficient to permit removal of the spacer plate 60 by swinging the member 63 outwardly about the column 11 and to leave a volume of sand in excess of the reduced cavity defined by the flask walls and the bottom pattern plate as best shown in Fig. 8 of the drawings. The lift table 25 is again moved to clamp the bottom pattern plate and flask against the blow plate assembly and the sand is compacted in the reduced cavity thus formed. After the squeezing operation, the lift table returns and deposits the mold on rails 22 and withdraws the pattern. As will hereinafter be more fully explained, the draw speed is decreased during separation to protect the mold. Although the foregoing operations may be accomplished by hand, the foregoing operations can be automatically accomplished in predetermined sequence in a continuous sand blowing cycle by means of suitable conventional controls.

Since it is necessary to lower the lift table 25 sufficiently to permit removal of the spacer plate 60 prior to the compacting operation, it will be apparent that in the construction of the apparatus disclosed there must be a limit 30 to the extent that the lift table may be lowered in order to prevent separation of the pattern plate from the flask (see Fig. 7). This is preferably accomplished in accordance with this invention by controlling release of hydraulic fluid from the cylinder housing 31 in such a manner as 35 to provide a dashpot operation for the plunger 30. Thus, initially when fluid under pressure is applied to lift the table 25 it may also be supplied to the cylinder 31 and, after the mold cavity is filled with sand and the main plunger 26 is lowered, the hydraulic fluid is blocked in 40 the cylinder 31 to provide a limiting downward stop for lift table 25. The same arrangement is utilized to decrease the draw speed of the lift table during separation of the pattern from the mold. Operation of the dashpot can be controlled by conventional valves and the like and 45 by adjusting the stroke of the plunger 30 in the cylinder 31.

Thus, there has been provided an improved sand blowing apparatus for making sand molds and cores or the like and having a more efficient and highly productive arrangement for presenting the proper patterns and for 50 removing and unloading the completed molds or cores. There has also been provided a simple arrangement for utilizing the main lift table in conjunction with a spacer member to permit compacting of the sand within the mold cavity. The latter arrangement includes an improved dashpot type limit for the lift table movement to prevent separation of the pattern from the mold while the spacer plate is being removed prior to the sand compacting operation and to reduce the draw speed during separation of the pattern from the mold. The improved apparatus permits the making of cope and drag on a single machine and provides greater accessibility for inspection and replacement of patterns during operation. Each of these improvements contribute to the overall efficiency and to increased production in a manner that 55 results in the optimum formation of sand molds and cores which are sufficiently compressed to withstand metal pressures in later use.

I have shown and described what I consider to be the preferred embodiment of my invention along with 60 suggested modified forms, and it is clear that other changes and modifications may be made by those skilled in the art without departing from the scope of my invention as defined by the appended claims.

I claim:

1. In a sand blowing apparatus having a frame includ-

ing a pattern support adapted to be surmounted by a flask or core box, a multiple pattern carrier rotatably mounted on the frame and adapted to support independent patterns in spaced relation from each other, said carrier having at least a pair of circumferentially displaced carrier portions each adapted to independently support a pattern thereon, the displacement being such that while one pattern is positioned by the carrier in operative position on the pattern support at least another pattern is accessible to an operator external to the support and frame, said pattern support comprising a lift table adapted for vertical movement relative to the frame, each of said carrier portions including an open-ended frame disposed with the open ends facing each other on opposite sides of the lift table, each of said open-ended frames defining a boundary complementary to the peripheral configuration of the lift table, whereby vertical movement of said table will lift the pattern away from the carrier and towards the surmounting flask or core box.

2. In a sand blowing apparatus having a frame including a vertical column disposed adjacent a pattern support, said pattern support being adapted to be surmounted by a flask or core box, a multiple pattern carrier rotatably mounted on the frame column and adapted to support independent patterns in spaced relation from each other, said carrier having at least a pair of circumferentially displaced carrier portions each adapted to independently support a pattern thereon, each of said carrier portions comprising an open ended frame defining a boundary complementary to the peripheral configuration of the pattern support and being adapted to receive the pattern support within its boundaries beneath the pattern, said carrier portion frames having their open ends facing each other from opposite sides of the pattern support whereby rotation of the pattern carrier selectively positions one or the other of the carrier portions in active position relative to the pattern support depending upon the direction of rotation, and means adapted for selective coaction therebetween to transfer the pattern from the active carrier portion to said support.

3. In a sand blowing apparatus having a frame adapted to support a mold flask or core box in operative position to form an enclosed sand receiving cavity between a spaced sand discharge chamber and a bottom pattern element, a clamping member, said last mentioned member being reciprocable in a vertical direction, a support on the frame having a marginal configuration adapted to support only the flask or core box wall boundaries in surmounting spaced relationship from the pattern element, a multiple pattern carrier rotatably mounted on the frame and adapted to support independent patterns in spaced relation from each other, said carrier having at least a pair of circumferentially displaced carrier portions each adapted to independently support a pattern thereon, the displacement being such that when one pattern is positioned by the carrier in operative position with respect to the clamping member at least another pattern is accessible to an operator external to the clamping member and frame, each of said carrier portions including an open-ended frame disposed with open ends generally facing each other on opposite sides of the clamping member,

each of said open-ended frames defining a boundary generally complementary to the peripheral configuration of the clamping member, a spacer member, means rotatably mounted on said apparatus frame above said flask or core box support and above said carrier for supporting said spacer member in a plurality of positions with respect to said sand receiving cavity, said spacer member being selectively movable into and out of the space between the discharge chamber and sand receiving cavity depending upon the direction of rotation of said means and being vertically movable with respect to the latter when engaged by said flask or core box, said spacer member having an opening therethrough of a configuration substantially coincident with the flask or core box walls of the sand receiving cavity when said means is rotated to position said spacer member into said space, whereby the volume of the enclosed cavity is increased by the thickness of the spacer member, said clamping member being operative upon upward movement thereof to lift the pattern element away from said carrier, the flask or core box away from its support, and the spacer member away from its supporting means, all towards said sand discharge chamber, and means for selectively limiting retraction of said clamping member to permit outward rotation of said spacer member supporting means and resultant removal of the spacer member from said space without separation of the pattern element from the flask or core box, whereby said clamping member may be reapplied to compact the sand in the lesser sand receiving cavity with the spacer member removed.

4. In a sand blowing apparatus in accordance with claim 3 wherein said apparatus frame comprises a plurality of vertical columns disposed generally adjacent said clamping member, said carrier being rotatably mounted on one of said columns, said spacer member supporting means being rotatably mounted on another of said columns, said spacer member supporting means comprising a sleeve element concentrically mounted in movable relationship on said other column and a generally horizontally extending U-shaped arm element for supporting said spacer member thereon, said spacer member comprising an interchangeable spacer plate having an opening corresponding to the particular type and size of associated flask or core box, and means on said arm element and on said spacer plate adapted for interlocking coaction in a horizontal plane to align the spacer plate opening with the flask or core box opening.
